Inventor;

William Sims

United States Patent Office.

WILLIAM SIMS, OF PITTSBURG, PENNSYLVANIA.

Letters Patent No. 65,773, dated June 11, 1867.

IMPROVED DOOR AND BIT FOR BOILING AND PUDDLING FURNACES.

The Schedule referred to in these Letters Patent and making part of the same.

TO ALL WHOM IT MAY CONCERN:

Be it known that I, WILLIAM SIMS, of No. 774 Penn street, in the city of Pittsburg, county of Allegheny, and State of Pennsylvania, have invented a new and improved Door and Bit for Puddling or Boiling Furnaces, or all other furnaces subject to extreme heat; and I do hereby declare that the following is a full and exact description thereof, reference being had to the accompanying drawings, and to the letters of reference marked thereon.

Figure 1 is an inside view of my improved door and new bit.

Figure 2 is a view of the bottom of the same.

Figure 3 is a vertical central section through the section line A B of fig. 1; and

Figure 4 is a section through the section line E D of fig. 1.

Similar letters of reference indicate like parts.

F is my improved door, which is filled with the fire-brick G G, four of which are removed to show my new bit and the manner of securing the same to the door. H is my bit, having the wings C C and the flanges J J, which are connected to the wings by the brackets K K. The bit is securely fastened to the door by the bolts L L, which pass through the door and are fastened either by a nut or key. The ledges M M on the bottom of the door secure the flanges J J and support the bit, preventing all vibratory motion and relieving the bolts L L of the weight of the bit.

The nature of my invention consists in the peculiar formation of the door and bit, as follows: The wings of the bit, marked C C in the drawing, with brackets on each side acting as supports or stays to the wings, are intended to be, and they are, a protection to the door from the action of the fire in the furnace, the wings, as noted above, taking the place of that portion of the door which is always destroyed by the action of the fire, and thus rendering the whole door useless, whereas under this improvement the door is saved and the bit only destroyed. That from the peculiar construction of the bit, which forms the mouth of the door, and can be readily detached, and the filling in with fire-brick or other substances between the sides of the door and the bit, the door will stand the same intensity of heat which is common to the ordinary furnace door at the present time for a much longer period, and when injured or destroyed by the fire or any other cause can be easily taken out and replaced by a new bit, without casting aside the whole door as heretofore, thereby saving in time and expense.

The door with this improvement would last an indefinite length of time, while the door in use at present would be destroyed in a few weeks used in the same way. This improvement in a mill of twenty furnaces, it is believed, would save more than \$1,000 per annum in the cost of doors alone, besides the economy of time and the destruction of brick or other substance used for lining or filling the inside of the door.

What I claim as my invention, and desire to secure by Letters Patent, is—

An improved door and a new bit to be fastened thereon for puddling or boiling furnaces, or all other furnaces subjected to intense heat.

WILLIAM SIMS.
